UNITED STATES PATENT OFFICE.

JOHN VAN WUYCKHUYSE, OF ROCHESTER, NEW YORK.

DESIGN FOR A ROCKING-HORSE.

• 54,879.

Specification for Design. Patented Apr. 13, 1920.

Application filed October 1, 1919. Serial No. 327,794. Term of patent 7 years.

To all whom it may concern:

Be it known that I, JOHN VAN WUYCKHUYSE, a citizen of the United States, residing at Rochester, in the county of Monroe and State of New York, have invented a new and original Design for Rocking-Horses, of which the following is a specification, reference being had to the accompanying drawing, forming a part thereof.

The figure of the drawing is a perspective view of the rocking horse showing my new design.

I claim:

The ornamental design for a rocking horse as shown.

In testimony whereof I affix my signature.

JOHN VAN WUYCKHUYSE.
